UNITED STATES PATENT OFFICE.

EMILE JEAN JULES SALMSON, OF BILLANCOURT, FRANCE, ASSIGNOR TO SOCIETE DES
MOTEURS SALMSON (SYSTEME CANTON-UNNE), OF BILLANCOURT, FRANCE.

AEROPLANE BODY OR CELL.

1,308,810.

Specification of Letters Patent.

Patented July 8, 1919.

Application filed March 14, 1916. Serial No. 84,113.

To all whom it may concern:

Be it known that I, EMILE JEAN JULES SALMSON, citizen of the Republic of France, residing at 9 Avenue des Moulineaux, Billancourt, Seine, in the Republic of France, have invented new and useful Improvements in Aeroplane Bodies or Cells, of which the following is a specification.

This invention relates to an improved body or cell for aeroplanes having at least two decks the essential feature of said body or cell lying in the fact that the decks are connected one to each other by crossed posts which are secured together at their crossing points.

In the annexed drawing which illustrates diagrammatically a double deck aeroplane body or cell incorporating the invention,

Figure 1 is a front elevation view of a part of the body or cell,

Fig. 2 is a side view of same.

Referring to the drawing it will be seen that the aeroplane body or cell in the example illustrated is formed of two wings or decks *a* and *b* the front beams *c¹*, *c²* and the rear beams *d¹*, *d²* of which are respectively braced together by means of crossed posts such as *e* and *f*. These posts are secured together at their middle or crossing points *g*.

One of the advantages of this arrangement lies in the fact that the part of the post

which is submitted to the flexure or bending produced by the axial compression is smaller than the distance between the two decks. This arrangement allows also of reducing the number of tension wires and even of suppressing them entirely; besides the crossing points *g* of the posts can be used as bearers to support the gear casings, the screw propellers, the car, fuel or other tanks, and the like.

Having now described my invention, what I claim as new and desire to secure by Letters Patent is:

In an aeroplane comprising a plurality of decks having front and rear beams all of which are substantially parallel to each other, the combination of crossed posts extending from each front beam to a front beam of the next deck above or below and secured to each other at their crossing points, and similar crossed posts extending from each rear beam to a rear beam of the next deck above or below and secured to each other at their crossing points.

In testimony whereof I have signed my name to this specification in the presence of two subscribing witnesses.

EMILE JEAN JULES SALMSON.

Witnesses:

ANTOINE LAVOIX,
CHAS. P. PRESSLY.
